UNITED STATES PATENT OFFICE.

PHILANDER C. T. CHEN, OF CHICAGO, ILLINOIS.

COMBINATION PENCIL AND FOUNTAIN PEN.

Application filed April 21, 1923. Serial No. 633,585.

To all whom it may concern:

Be it known that PHILANDER C. T. CHEN, a citizen of the United States, residing at Chicago, in the county of Cook and State of

5 Illinois, has invented certain new and useful Improvements in Combination Pencils and Fountain Pens, of which the following is a specification.

In carrying out the present invention it is 10 my purpose to provide a combined article that may be advantageously employed as either a fountain pen or pencil, the article being equipped with a cap for ready disposition upon opposite ends thereof for enclosing 15 either the pen or pencil when the opposite element is being used.

A further purpose of the invention is the provision of such a combined article wherein the pencil element per se is of the 20 eversharp type, a highly improved means being provided for feeding the lead outwardly of its maintaining barrel whenever desirable.

A still further purpose of the invention re- 25 sides in the provision of such an article that is comparatively simple in construction and one that may be manufactured and marketed at relatively small cost.

The nature and advantages of the invention 30 will be better understood when the following detailed description is read in connection with the accompanying drawings, the invention residing in the construction, combination and arrangement of parts 35 as claimed.

In the drawings forming part of this application, like numerals of reference indicate similar parts in the several views, and wherein:—

40 Figure 1—is a side elevation of my combined article,

Figure 2—is a detail longitudinal cross section thereof,

45 Figure 3—is an enlarged side elevation of the pencil element removed from the main barrel,

Figure 4—is a detail cross section taken substantially on the line 3—3 of Figure 4, and

50 Figure 5—is a longitudinal cross section upon the line 5—5 of Figure 3.

Referring to the drawings in detail, 5 indicates a relatively elongated hollow barrel provided internally and adjacent one end

55 with a partition 6 for dividing said barrel into chambers 7 and 8 at opposite ends

thereof. Within the chamber 7 there is positioned the usual rubber ink well 9 of a fountain pen designated generally 10, and the same being of a conventional form. 60

The chamber 8 is screw threaded for the major portion of its length, these screw threads being disrupted adjacent the outer end of the chamber for providing a relatively wide channel 11, the purposes presently to 65 be set forth.

Within the chamber 8 there is adapted to be positioned a pencil element designated generally 12, the same comprising a pair of spaced parallel, somewhat arcuate-shaped 70 lead receptacles 13 integrally joined at their front ends by a conical head 14; the opposite ends of these lead receptacles 13 are open, and are adapted to be closed by an end plug 75

Slidable between the receptacles 13 is a cross head 16, the ends of which project outwardly of the sides of said article, and are screw threaded at 17 for threaded engagement with the threads of said chamber 8. 80 This head is provided with a suitable form of clamp to which is secured one end of a strip of lead 18 that is adapted to be projected through a passage 19 in said head 14, when the pencil element 12 is rotated within 85 the chamber.

Each of the said receptacles 13 is provided with a raised cross threaded portion 20 adjacent its headed end, adapted for inter-engagement with the screw threads at the front 90 end of said chamber, whereby a turning movement of the head 14 of the pencil element in one direction will occasion the engagement of said pencil element within the chamber. A continued turning movement of 95 said head will bring the threaded raised portions 20 into the channel 11 for consequently allowing a rotation of the pencil element with respect to the barrel 5 in either direction without affecting the relation of the 100 pencil element to the interior of said chamber 8.

Whenever it is desired to remove the pencil element, a slight pull is applied between the head of the pencil element and the barrel 5, at which time, it is rotated with respect to the barrel for consequently engaging the threads of the raised portions 20 with the threads of the chamber, for withdrawing the pencil element therefrom. 105

The barrel 5 is formed externally with screw threads 21 adjacent one end, and with 110

2
screw threads 22 at its opposite ends for receiving internal screw threads of a closure cap 23. The closed end of this cap 23 is provided with a screw threaded opening for receiving either end of an externally screw threaded sleeve 24 formed centrally with a flange 25 adapted to bring up against the end of said cap. The sleeve 24 carries a rubber eraser 26 either end of which may be employed by merely reversing the sleeve within the cap 23, it being well to note that one end of this eraser 26 is an ink eraser and the opposite end is a pencil eraser.

10 In view of the above description it is believed by me that the operation and advantages of an article of this character will be readily appreciated by those skilled in the art and although I have herein shown and described the preferred embodiment of the 20 present invention, it is nevertheless to be

understood that minor changes may be made therein, without departing from the spirit and scope of the invention as claimed.

Having thus described my invention, what I claim as new and wish to secure by Letters Patent, is:

A writing implement comprising a barrel provided at its end with a chamber having an internally threaded wall, a plug for closing the end of the chamber and carrying at 30 its inner end oppositely disposed receptacles adapted to enter the chamber, a cross head adapted to enter the chamber and disposed transversely thereof, said cross head being provided with thread sections at its ends 35 adapted to engage the threaded chamber, and a lead carried by the cross head and passing through the plug.

In testimony whereof I affix my signature,
PHILANDER C. T. CHEN.
